DESCRIPTION

FIG. 1 is a perspective view of an electric coffee maker showing my new design;

FIG. 2 is a left side elevational view of the electric coffee maker of FIG. 1.

FIG. 3 is a right side elevational view of the electric coffee maker of FIG. 1.

FIG. 4 is a top plan view of the electric coffee maker of FIG. 1.

FIG. 5 is a perspective view of the electric coffee maker of FIG. 1.

FIG. 6 is a perspective view of the electric coffee maker of FIG. 1 without a carafe

FIG. 7 is a front elevational view of the electric coffee maker of FIG. 1 with different environmental elements.

FIG. 8 is a front elevational view of the electric coffee maker of FIG. 1 with different environmental elements; and,

FIG. 9 is a front elevational view of the electric coffee maker of FIG. 1 with different environmental elements.

The rear of the claimed design is not shown in the drawing or described in the specification. It is understood that the appearance of any part of the article not shown in the drawing or described in the specification forms no part of the claimed design. Therefore, the determination of patentability is based on the design for the article shown and described.

The broken lines appearing in the figures are for the purpose of illustrating the environmental structure of the article of the claimed design and form no part of the claimed design.
